[57] CLAIM

The ornamental design for a toy rake, as shown and described.

DESCRIPTION

FIG. 1 is a top plan view of a toy rake showing a first embodiment of my new design;

FIG. 2 is a front elevational view thereof and is also a mirror image of rear elevational view thereof;

FIG. 3 is a left side elevational view thereof;

FIG. 4 is a right side elevational view thereof;

FIG. 5 is a bottom plan view thereof;

FIG. 6 is a sectional view taken in the direction of the arrows on line VI—VI of FIG. 1;

FIG. 7 is a top plan view of a toy rake showing a second embodiment of my new design;

FIG. 8 is a front elevational view thereof and is also a mirror image of rear elevational view thereof;

FIG. 9 is a left side elevational view thereof;

FIG. 10 is a right side elevational view thereof;

FIG. 11 is a bottom plan view thereof; and,

FIG. 12 is a sectional view taken in the direction of the arrows on line XXII—XXII of FIG. 7.
